CONVERSION OF HYDROCARBONS

Gustav Egloff and Vasili Komarewsky, Chicago,
Ill., assignors to Universal Oil Products Com-
pany, Chicago, Ill., a corporation of Delaware

Application January 27, 1941, Serial No. 376,030

4 Claims. (Cl. 196—54)

This invention is concerned with the conversion of relatively heavy fractions of petroleum, such as the gas oil fractions, into substantial yields of gasoline of both a high antiknock and a saturated character.

The invention is more specifically concerned with the treatment of heavy fractions of petroleum with a metal halide catalyst in a combination of steps involving a primary cracking treatment followed by an isomerization treatment of the cracked gasoline which comprises essentially a reforming operation without the occurrence of undesirable amounts of decomposition reactions resulting in losses of gas and heavy carbonaceous residues.

It is recognized as being known in the art to use metal halides as catalysts in cracking heavy distillate fractions of petroleum to produce gasoline boiling range materials therefrom. In general, the use of catalysts such as aluminum chloride, ferric chloride, zirconium chloride and zinc chloride in cracking reactions tends to produce both gas and gasoline distillates of a saturated character in contra-distinction to the gasolines produced by strictly thermal cracking or in the presence of other types of catalysts such as metals or metal oxides which have more of a splitting action on the carbon to carbon bond resulting in the formation of varying yields of hydrocarbons having both mono- and di-olefinic unsaturation. The gasoline boiling range from these types of operations frequently require special supplementary treatments to render the gasoline marketable in respect to color and gum formation and stability in respect to antiknock value on storage in refineries in contact with air.

Such supplementary treatments include treatment with sulfuric and other acids, hydrogenation, inhibitors and many other methods of treatment.

While the gasolines produced by aluminum chloride cracking, as typical of processes employing various catalytically active metal halides, are essentially saturated, we have found that benefits are obtained if the gasoline primarily produced is subjected to further treatment with metal halides having an isomerizing action on the hydrocarbons in the primary gasolines. The magnitude of these effects will be developed later in the present description in connection with the examples introduced.

In one specific embodiment the present invention comprises a process for converting relatively heavy hydrocarbon fractions containing substantially no gasoline into substantial yields of

saturated gasoline of relatively high antiknock value which comprises continuously treating said heavy fractions with aluminum chloride and hydrogen chloride to produce substantial yields of gasoline boiling range products, fractionating conversion products to produce gases, gasoline, intermediate insufficiently converted refluxes and residual material, recovering said gases and said residual material, returning said insufficiently converted refluxes to further conversion, subjecting said gasoline to further treatment with aluminum chloride and hydrogen chloride to improve the antiknock value thereof, fractionating the products from the gasoline treatment to produce gas, isomerized gasoline and residual materials consisting of fractions amenable to further conversion and partly spent aluminum chloride, separately recovering said gas and said isomerized gasoline and returning said residual material to the primary conversion zone.

The essential steps of the present process will be developed in connection with the attached drawing which shows by the use of conventional figures in side elevation an arrangement of interconnected units by which the process may be carried out. The drawing is not made to any absolute or relative scale and is merely used to illustrate the general type of flow which characterizes the process of the present invention.

Referring to the drawing, a hydrocarbon charging stock such as a petroleum gas oil fraction or naphtha is introduced to the plant through a line 1 containing a valve 2 to a charging pump 3 which discharges into line 4 containing a valve 5 and thence through a heating element 16 disposed to receive heat from a furnace 17. The necessary amounts of substantially anhydrous aluminum chloride may be introduced in the form of a slurry in a substantially unreactive hydrocarbon fraction by way of line 6 containing a valve 7 to charging pump 8 which discharges through line 9 containing a valve 10 into line 4. The hydrogen chloride essential for the conversion reactions is introduced through line 11 containing a valve 12 to charging pump or compressor 13 which discharges through line 14 containing a valve 15 to line 4. Line 4 also receives primary cracked refluxes from line 31 and secondary refluxes from line 75 along with partly spent catalysts.

The proportions of hydrocarbons, aluminum chloride and hydrogen chloride are selected to produce optimum over-all results, but in general, the amounts of aluminum chloride will be less than 10% of the weight of the oil, and the

amounts of hydrogen chloride will be of the order of from 1 to 5% of the weight of the oil. While the hydrogen chloride is thus evidently in minor amounts its presence is nevertheless essential to the conversion reactions.

During the passage of the mixture of oil, aluminum chloride and hydrogen chloride through heating element 16 it is brought to some temperature in the approximate range of about 300-700° F. to effect the desired conversion reactions while using pressures of the order of from 50 to 400 pounds per square inch, the heated products passing through line 18 containing a valve 19 to lower space 21 of fractionator 20 which has been drawn as a single fractionator, but which is intended to indicate one comprising any arrangement of elements which will effect the desired separations. Line 26 containing a valve 27 is provided for withdrawing spent catalyst and the process is preferably operated so that the residual material retains sufficient fluidity to permit continuous withdrawal and recovery of the active catalyst or other decomposition products.

The vapors from lower section 21 pass through line 22 containing a valve 23 to the upper portion of the fractionating column which is preferably operated so that mixed gases containing less than four carbon atoms per molecule are withdrawn through line 24 containing a valve 25 while butanes are withdrawn through line 33 containing a valve 34 and the pentane fraction through line 35 containing a valve 36. The refluxes amenable to further catalytic conversion may be withdrawn through line 28 containing a valve 29 to recycling pump 30 which discharges through line 31 containing a valve 32 back to charging line 4.

In accordance with the present invention, a gasoline fraction, say one boiling between the approximate range of 100-400° F. is removed as a side-cut through line 37 containing a valve 38 to a pump 39 which discharges through a line 40 containing a valve 41 through a secondary heating element 52 disposed to receive heat from a furnace 53. In a manner analogous to the primary conversion step, aluminum chloride either in a finely divided condition as such or on a support may be introduced as a relatively concentrated slurry by way of line 47 containing a valve 48 to pump 49 which discharges through a line 50 containing a valve 51 into line 40. Requisite amounts of hydrogen chloride essential for the succeeding isomerization treatment may be introduced through line 42 containing a valve 43 to feed pump or compressor 44 which discharges through line 45 containing a valve 46 into line 40.

The conditions necessary for further isomerizing the hydrocarbons in the primary gasoline to raise the over-all antiknock value thereof will again vary with such factors as the type of oil originally charged to the plant, the degree of conversion and the susceptibility of the individual hydrocarbons to isomerizing treatment so that only broad ranges or conditions can be laid down. While it is probable that isomerization reactions predominate in the secondary reforming step of the process, it is probable that other reactions take place to add to the overall reforming effect. These reactions may involve carbon to carbon splitting, dehydrogenation, particularly of naphthenes, and various types of alkylation and hydrogen transfer reactions. The range of temperatures most commonly employed in the re-

forming step are from about 125 to about 500° F., and pressure may be employed if desired to increase the capacity of the unit although apparently pressure has very little independent effect. Rates of flow will also require adjustment to give the proper time of contact for effecting optimum treatment.

The products from heating element 52 pass through line 54 containing a valve 55 to a final fractionator 56 adapted to segregate fixed gases, gasoline boiling range fractions and heavy recycled materials. Line 57 containing a valve 58 permits the withdrawal of fixed gases which can be further fractionated if desired to separate hydrogen chloride for recycling to either step of the process, although means for accomplishing these ends are not shown in the drawing.

Gasoline boiling range materials of improved antiknock value are withdrawn through line 59 containing a valve 60 and passed through condenser 61 and thence to line 62 containing a valve 63 to receiver 64 which is shown provided with a conventional gas-release line 65 containing a valve 66 and a liquid draw-line 67 containing a valve 68.

Heavy materials accumulating in the bottom of fractionator 56 are withdrawn through line 69 containing a valve 70 to a pump 71. These materials will usually consist of a small amount of heavy reflux containing partly spent suspended aluminum chloride. Since when operations are properly conducted there is a minimum of side reactions in the second step of the process the aluminum chloride slurry withdrawn through line 69 will still have potency in effecting the primary cracking reactions. Pump 71 discharges into line 72 containing valves 73 and 74 and having branch line 75 containing a valve 76 for recycling reflux to line 4. Valve 74 may be used to intermittently or continuously purge a certain amount of the spent catalyst if found desirable or necessary.

The following example is introduced as illustrative of the results normally obtainable in the operation of the present process although not with the intention of limiting the invention in exact correspondence with the data presented.

A Mid-Continent gas oil fraction was subjected to treatment, the cracking step being conducted at a temperature of 575° F. in the presence of about 10% by weight of finely divided granular and substantially anhydrous aluminum chloride and about 5% by weight of hydrogen chloride. In this stage of the process there was produced 46% of gasoline by volume of the oil charged, this gasoline having an octane number of 69 by the motor method of testing. This gasoline fraction was further treated with 6% by weight of granular aluminum chloride and 3% by weight of hydrogen chloride at a temperature of 350° F. which raised the octane number from 69 to 76 with a gas and residue loss of 5%.

We claim as our invention:

1. A process for converting a relatively heavy hydrocarbon fraction containing substantially no gasoline into substantial yields of saturated gasoline of relatively high antiknock value which comprises cracking said heavy fraction in the presence of aluminum chloride and hydrogen chloride in a primary conversion zone to produce substantial yields of gasoline boiling range products, fractionating conversion products to produce gases, gasoline, intermediate insufficiently converted refluxes and residual material, recovering said gases and said residual material, returning said insufficiently converted refluxes to further

conversion, subjecting said gasoline to further treatment with aluminum chloride and hydrogen chloride to improve the antiknock value thereof, fractionating the products from the gasoline treatment to produce gas, isomerized gasoline and residual material consisting of hydrocarbon fractions amenable to further cracking and partly spent aluminum chloride, separately recovering said gas and said isomerized gasoline and returning said residual material to the primary conversion zone.

2. A process for converting a relatively heavy hydrocarbon fraction containing substantially no gasoline into substantial yields of saturated gasoline of relatively high antiknock value which comprises cracking said heavy fraction at temperatures of from about 300 to about 700° F. under a pressure of from 50 to about 400 pounds per square inch in the presence of aluminum chloride and hydrogen chloride in a primary conversion zone to produce substantial yields of gasoline boiling range products, fractionating conversion products to produce gases, gasoline, intermediate insufficiently converted refluxes and residual material, recovering said gases and said residual material, returning said insufficiently converted refluxes to further conversion, subjecting said gasoline to further treatment at a temperature of from about 125° to about 500° F. with aluminum chloride and hydrogen chloride to improve the antiknock value thereof, fractionating the products from the gasoline treatment to produce gas, isomerized gasoline and residual materials consisting of hydrocarbon fractions amenable to further cracking and partly spent aluminum chloride, separately recovering said gas and said isomerized gasoline and returning said residual material to the primary conversion zone.

3. A continuous process for converting a relatively heavy hydrocarbon fraction containing substantially no gasoline into substantial yields of saturated gasoline of relatively high antiknock value which comprises cracking said heavy

- fraction at a temperature of from about 300 to about 700° F. under a pressure of from about 50 to about 400 pounds per square inch in the presence of aluminum chloride in an amount of less than 10% by weight of said hydrocarbon fraction and hydrogen chloride in an amount of from about 1 to 5% by weight of said hydrocarbon fraction in a primary conversion zone to produce substantial yields of gasoline boiling range products, fractionating conversion products to produce gases, gasoline, intermediate insufficiently converted refluxes and residual material, recovering said gases and said residual material, returning said insufficiently converted refluxes to further conversion, subjecting said gasoline to further treatment at a temperature of from about 125° to about 500° F. with aluminum chloride in an amount of less than 10% by weight of said hydrocarbon fraction and hydrogen chloride in an amount of from about 1 to 5% by weight of said hydrocarbon fraction to improve the antiknock value thereof, fractionating the products from the gasoline treatment to produce gas, isomerized gasoline and residual materials consisting of hydrocarbon fractions amenable to further cracking partly and spent aluminum chloride, separately recovering said gas and said isomerized gasoline and returning said residual material to the primary conversion zone.
4. A conversion process which comprises cracking hydrocarbon oil heavier than gasoline in the presence of aluminum chloride, fractionating the resultant products to separate gasoline fractions therefrom, subjecting gasoline fractions thus separated to further treatment with aluminum chloride under reforming conditions to improve the anti-knock value thereof, separating the reformed gasoline fractions from residual material comprising partly spent aluminum chloride and hydrocarbons amenable to cracking, and supplying at least a portion of said residual material to the aforesaid cracking step.
